CLAIM

The ornamental design for a speaker enclosure for raised floor installation, as shown and described.

DESCRIPTION

FIG. 1 is a top plan view of a speaker enclosure for raised floor installation showing our new design;

FIG. 2 is a side elevational view taken in the direction of arrows 2—2 in FIG. 1;

FIG. 3 is an end elevational view taken in the direction of arrows 3—3 in FIG. 1;

FIG. 4 is a side elevational view taken in the direction of arrows 4—4 in FIG. 1;

FIG. 5 is an end elevational view taken in the direction of arrows 5—5 in FIG. 1; and

FIG. 6 is a bottom plan view, taken in the direction of arrows 6—6 in FIG. 5.

FIG. 4

FIG. 5

FIG. 6
